UNITED STATES PATENT OFFICE.

JAMES W. McSHERRY, OF DUQUOIN, ILLINOIS.

CONTROLLING APPARATUS FOR ELEVATORS AND OTHER DEVICES.

1,309,648.

Specification of Letters Patent. Patented July 15, 1919.

Application filed February 15, 1919, Serial No. 277,275.

To all whom it may concern:

Be it known that I, JAMES W. McSHERRY, a citizen of the United States, residing at Duquoin, Illinois, have invented a certain new and useful Improvement in Controlling Apparatus for Elevators and other Devices, of which the following is a full, clear, and exact description, such as will enable others skilled in the art to which it appertains to 10 make and use the same.

This invention relates to devices of the character that are used for controlling the operation of elevators and various other mechanisms.

15 It is now the usual practice in coal mines to provide a signal for enabling the "cager" or operative in the mine who places the mine cars on the elevator cage to notify the engineer in charge of the hoisting mechanism 20 when the cage is ready to be raised. When a pneumatically operated signal is used it is the general practice for the cager in the mine to operate the signal before the mine car is run completely onto the cage. If, for 25 any reason, the cager is unable to arrange the mine car in proper position on the cage before the engineer starts the hoisting mechanism, considerable damage to the shaft of the mine and to the elevator cage is sure to 30 result, as there is not sufficient time to enable the cager to signal the engineer again or notify the engineer that the cage is not in readiness to be raised. When it is desired to hoist miners instead of coal the cager 35 operates the signal three times, the signal usually consisting of a bell. The engineer replies with one bell so as to notify the cager that the engineer has received the signal and the cager then permits the waiting miners to 40 get on the cage. When the miners are all on the cage the cager gives the engineer a signal of one bell as to notify the engineer that the cage is ready to be raised. Unless the engineer pays strict attention to the 45 signals he is apt to become confused and start the hoisting mechanism before all of the waiting miners have been loaded on the cage. Moreover, when a pneumatically operated bell is used there is danger of the air 50 in the tube backing up and causing the bell to ring accidentally, thus giving the engineer a false signal to hoist at the time when the miners are getting onto the cage. Accidents of the character referred to frequently occur in coal mines and add considerably to the cost of operating the mine,

due to the loss in production while the shaft is out of commission, and the cost of repairing the shaft timbers and the cage, and in some instances, the hoisting cable. 60 Furthermore, such accidents often result in serious injury or death to the mine operatives. In other lines of work where an engineer or operative is employed to start and stop an apparatus upon receiving signals 65 from a workman located at some distance from the apparatus, accidents frequently occur, due to premature starting of the apparatus by the engineer or failure to stop the apparatus after some unusual condition 70 arises, unknown to the engineer, which requires that the apparatus be stopped immediately to avoid an accident.

The main object of my invention, therefore, is to provide means by which an operative located at some distance from an apparatus or mechanism in charge of an engineer or other workman, can stop said apparatus or mechanism at will and independently of said engineer, thereby eliminating 75 the possibility of accidents in instances where there is not sufficient time for the workman located at the distant point to signal the engineer to stop the apparatus.

The specific object of my invention is to 80 provide a mine that is equipped with means by which the cager in the mine who places the mine cars on the cage can stop the hoisting mechanism of the elevator or prevent 85 said hoisting mechanism from being rendered operative in the event that some condition arises, after he has signaled the engineer to raise the cage, that would result in an accident if the cage were allowed to ascend.

Various means can be used for accomplishing the results above referred to without departing from the spirit of my invention, but when my invention is embodied in an elevator controlling apparatus for mines, as herein shown, I prefer to use a means under 90 control of the cager in the mine for closing the throttle valve of the engine that operates the hoisting mechanism, or for operating a brake that acts on the winding drum. In practice I prefer to provide means by which 95 the cager in the mine can close the throttle valve of the hoisting engine and also simultaneously apply the usual brake that acts on the winding drum by simply closing an electric switch that is arranged in the mine 100 in close proximity to the cager.

The figure of the drawings is a diagram.

matic view, illustrating my invention embodied in a mine.

Referring to the drawings. A designates the opening of a mine through which the material is taken out of the mine, said opening either consisting of a shaft or slope. B the elevator cage that travels in said opening, C the drum of the hoisting mechanism on which the cable D of the cage is wound, and 10 E a controlling device that governs the throttle valve of the engine (not shown), which operates the hoisting mechanism and which is normally under the control of an engineer. The hoisting drum is equipped 15 with a band brake F that can be operated either by a foot treadle G or by means of steam pressure that is admitted to a cylinder H whose piston is provided with a device I that acts on the treadle G and applies the 20 brake F when said piston moves downwardly, the supply of steam to the cylinder H being controlled by a valve I. The parts 25 above referred to are of well known construction and form part of the usual equipment of many coal mines.

In the form of my invention herein shown an electric magnet or other suitable device J is employed for causing the throttle valve of the hoisting engine to close and for causing the brake F to be applied whenever an 30 electric switch K in the mine is operated. The iron block J' acted on by said magnet is pivotally mounted and is provided with an arm 3 that is connected by a system of 35 links 4 with an arm 5 on the stem of the valve I that governs the admission of steam to the cylinder H. The controlling device E for the throttle valve of the hoisting engine is operatively connected with a piston 40 arranged in a steam cylinder L to which steam is admitted by a pipe 6 that is tapped into the steam supply pipe 7 in which the valve I is arranged. Whenever the magnet J is energized the valve I will open, and 45 thus admit steam to the cylinders H and L, thereby causing the brake F to be applied and the controlling device E to move in the direction to close the throttle valve of the hoisting engine. Any suitable kind of 50 switch K can be used for governing the electric circuit 8 that energizes the magnet J, but I prefer to use a knife switch whose handle is provided with a relatively large plate 9 of insulating material so as to enable the cager to close the switch by simply 55 striking said plate a blow.

If the cager signals the engineer to hoist and then runs the mine car 2 onto the cage B, as is the usual practice in coal mines, 60 and if the dogs 10 on the cage that control the position of the mine car fail to operate due to being jammed by coal lying on the track, the mine car is apt to assume such a position on the cage that it will strike 65 against the top of the drift when the cage

moves upwardly. The engineer starts the hoisting mechanism as soon as he receives the hoisting signal and the cage starts to move upwardly, but as soon as the cager notices that the mine car is in an improper 70 position on the cage, he closes the switch K. The cage immediately stops, due to the closing of the throttle valve of the hoisting engine and the application of the brake F to the hoisting drum C, thereby preventing an 75 accident that would result in injury to the shaft, cage and mine car, and possibly to the cager. From the foregoing it will be seen that my invention materially reduces the liability of accidents in mines, due to raising 80 the cage at the wrong time, for the cager in the mine can render the hoisting mechanism inoperative after he has signaled the engineer to hoist or can stop the hoisting mechanism in case the cage has started to ascend, 85 by simply closing the switch K. Any other suitable means than the one herein shown could be employed for stopping the hoisting mechanism or rendering it inoperative and various other means than an electrically actuated device could be employed for operating or governing the operation of the means 90 that stops the hoisting mechanism or renders it inoperative. Therefore, I wish it to be understood that my broad idea is not limited to 95 an apparatus or device of the particular construction herein illustrated. Furthermore, while I have herein illustrated my invention embodied in an elevator controlling apparatus for mines, my broad idea is applicable to 100 many other lines of work where an operative stationed at one point signals an operative at a different point in charge of an apparatus or mechanism when it is desired to 105 have said apparatus start operating.

Having thus described my invention, what I claim and desire to secure by Letters Patent, is:

1. In a mine, the combination of an elevator cage that travels in the opening 110 of the mine, a hoisting mechanism for said cage, a governing means for said hoisting mechanism adapted to be controlled by an engineer stationed outside of the mine opening, and means whereby an operative stationed in the mine can stop the elevator cage at will independently of said engineer.

2. In a mine, the combination of an elevator cage that travels in the opening 120 of the mine, a hoisting mechanism for said cage comprising a controlling device and a braking device adapted to be operated by an engineer stationed outside of the mine opening, an electrically-actuated means arranged in proximity to said hoisting mechanism for rendering said controlling device 125 inoperative and said braking device operative, and means under control of an operative stationed in the mine for energizing said electrically-actuated means so as to 130

stop the elevator cage independently of said engineer.

3. In an elevator controlling apparatus for mines, an elevator cage, a hoisting mechanism for said cage comprising a drum and a throttle controlling member, a brake for said drum, devices for applying said brake and for actuating said throttle controlling member, and means under control of an operative stationed in the mine for rendering said devices operative so as to stop the elevator cage independently of the engineer in charge of the hoisting mechanism.

4. In an elevator controlling apparatus for mines, an elevator cage, a hoisting mechanism for said cage comprising a drum and a throttle controlling device, a brake for said drum, steam operated devices for applying said brake and for actuating said throttle controlling device, a valve for ad-

mitting steam to said steam operated devices, and means under control of an operative in the mine for opening said valve.

5. In an elevator controlling apparatus for mines, the combination of an elevator cage, a hoisting drum, a throttle controlling device for governing the means that actuates the drum, a brake for said drum, a pressure operated device for applying said brake, a pressure operated device for moving said throttle closing device in a direction to stop the hoisting mechanism, a valve for admitting a medium under pressure to both of said pressure operated devices, an electric magnet for opening said valve, and an electric switch arranged in the mine in proximity to the place where the elevator cage is loaded for controlling the circuit that energizes said magnet.

JAMES W. McSHERRY.
